UNITED STATES PATENT OFFICE

121,701

DESIGN FOR A WIRE TOP FOR KEY CHAINS OR THE LIKE

James T. Rawlings, Rochester, N. Y., assignor to
Hickok Manufacturing Company, Inc., Rochester,
N. Y., a corporation of New York

Application January 22, 1940, Serial No. 89,636

Term of patent 7 years

To all whom it may concern:

Be it known that I, James T. Rawlings, a citizen of the United States, residing at Rochester, in the county of Monroe and State of New York, have invented a new, original, and ornamental Design for a Wire Top for Key Chains or the like, of which the following is a specification, reference being had to the accompanying drawing, forming part thereof.

In the drawing:

Fig. 1 is a front elevational view of a wire top for key chains or the like, showing my new design;

Fig. 2 is a side elevational view; and

Fig. 3 is a longitudinal sectional view taken on line 3—3 of Fig. 1.

I claim:

The ornamental design for a wire top for key chains or the like, substantially as shown.

JAMES T. RAWLINGS.
